UNITED STATES PATENT OFFICE

OSCAR A. OLSON, OF ST. PAUL, MINNESOTA

GARMENT HANGER

Application filed February 16, 1928. Serial No. 254,763.

This invention relates to a garment hanger, and has particular reference to that type of coat and trousers hanger made of a single piece of wire bent to provide a suspension hook, coat shoulder supporting portions, and a transverse member from which trousers may be suspended.

I am aware of many garment hangers having transverse members, but in most instances the trousers may slide from one side of the transverse member to the other side and eventually become displaced. In other instances, while means is provided to hold or prevent the sliding or displacement of the trousers, the construction is either objectionable because inefficient or frail, or because of not being extremely simple and economical to manufacture.

My invention aims, therefore, to provide a garment hanger of extremely simple and durable construction, and having readily constructed and applied means for positively holding the trousers against sliding or displacement.

The present invention consists in the novel form, combination and arrangement of parts hereinafter more fully described, shown in the accompanying drawing and claimed.

In the drawing:

Figure 1 is an elevation of a garment hanger constructed in accordance with the present invention; and

Figure 2 is a section on line 2—2 of Figure 1.

The hanger proper is fashioned from a single piece of wire bent to provide a transverse trouser supporting member 5, shoulder portions 6, a twisted shank 7, and a suspension hook 8.

Associated with and disposed above the transverse member 5 is a clamping arm 9 formed of a single piece of resilient wire and having one end firmly secured to an end of the transverse member 5 by twisting them together, as at 10. The clamping arm 9 extends in the same general direction as the member 5 and is tensioned to normally spring upwardly from the latter to released position as shown by dotted lines in Figure 1.

A clamping ring 11 is secured over the mem-

ber 5 and movable onto the adjacent free end of the clamping arm 9 to positively and releasably hold it in downwardly sprung position, as shown by full lines in the drawing, whereby the trouser is firmly clamped on the intermediate portion of the transverse member 5 against accidental displacement or sliding movement. By sliding the ring 11 off of the end of the clamping arm 9 to the dotted line position of Figure 1, the trouser will be released for free removal from the member 5. Obviously, the shoulder portions 6 are used to hang a coat, vest or the like.

From the above description, it will be apparent that the construction is extremely simple and durable, may be economically manufactured, and embodies efficient means for holding trousers against displacement.

What I claim as new is:

In a garment hanger, a body constructed from a single strand of wire and including shoulder portions, a suspension hook, and a transverse trouser supporting member interconnecting the shoulder portions, one end of the trouser supporting member being upwardly offset, a clamping arm having one end twisted around the offset portion of the transverse trouser supporting member, said arm extending above and in spaced relation with respect to said supporting member for receiving the trouser therebetween, the clamping arm being tensioned to normally spring upwardly at its free end, and a locking sleeve slidable on the other end portion of the supporting member for disposition over the free end of the clamping arm for releasably holding the latter in clamping engagement with the trouser disposed over the supporting member.

In testimony whereof I affix my signature.

OSCAR A. OLSON.
